UNITED STATES PATENT OFFICE.

CONRAD SCHIFFERLY, OF NORTH MANCHESTER, INDIANA.

IMPROVEMENT IN RECIPROCATING CHURNS.

Specification forming part of Letters Patent No. 149,609, dated April 14, 1874; application filed January 23, 1874.

To all whom it may concern:

Be it known that I, CONRAD SCHIFFERLY, of North Manchester, Wabash county, Indiana, have invented a new and useful Improvement in Churns, of which the following is a clear, full, and exact description, reference being had to the accompanying drawings, making a part of this specification, in which the figure represents a vertical section.

My invention relates to that class of churning in which the dasher and dasher-rod are used; and it consists in the combination and arrangement of the several parts, as hereinafter described.

To enable others skilled in the art to make and use my invention, I will describe the exact manner in which I have carried it out.

In the drawing, A is the ordinary churn; B, the dasher-rod; and b b', a compound dasher secured in position by the braces 1 and 2, the one above the other, a distance about equal to the diameter of the dasher. To the dasher-rod B is secured the conical-shaped guard B', at a point which will enable the guard to move within the tube C, the lower or larger part of the guard fitting loosely with the said pipe. The pipe C passes through and is rigidly secured to the top c, and extends about an equal distance above the top, and down into the body of the churn—say, about twelve inches, more or less, according to the size of the churn. The upper portion of this pipe is drawn in, as shown at c'; so as to snugly fit around the dasher-rod at that point. An orifice is made

in the tube C to admit air to the cream. D is a crank-shaft, by which the churn-dasher is operated, having its bearings in the framework d d', which in turn rests on the top of the churn by means of the arm F, while the lower portion k of the frame is securely held in the socket K on the side of the churn. To the inner end of the crank-shaft D is secured the wheel E, from near the periphery of which passes the bent rod e up to and attached at a point in the dasher-rod above the upper end of the pipe C, thus forming a pitman for working the dasher. The upper end of the frame d is secured to ferrule F' around the upper portion of dasher-rod B, and which acts as a guide and support for the rod.

From the foregoing description, it is evident that, while the dashers b b' are being operated by means of the crank D, wheel E, and pitman e, the cream is prevented from escaping by means of the guard B' and pipe C.

Having thus described my invention, what I claim as new, and desire to secure by Letters Patent, is—

In combination with the churn A and dasher-rod B, provided with the compound dasher b b', the guard B', and pipe C, constructed and arranged substantially as and for the purpose set forth.

CONRAD SCHIFFERLY.
